SAFETY RAZOR

Jan de Swart, Los Angeles, Calif., assignor of one-half to C. Bland Jamison, Beverly Hills, Calif.

Application April 9, 1943, Serial No. 482,411

11 Claims. (Cl. 30—47)

This invention relates to safety razors and embraces improvements upon the invention disclosed and claimed in my copending application Serial No. 455,160, filed August 18, 1942.

One of the principal objects of my present invention is the provision of simple, efficient and durable means of detachably securing the handle element to the guard plate, my improvements being particularly adaptable for, though not necessarily restricted to, the combination including the guard and clamping means shown and claimed in and by my said copending application.

Another object of the present invention is the provision of a telescopic handle and one including means for somewhat resiliently gripping the guard plate to produce a firm assembly as well as to compensate for wear.

A further aim is the provision of improvements in the blade-retaining means as well as in the clamping plate.

A still further object concerns improvements in the means of mounting the clamping plate on the guard.

Additional objects and advantages are inherent in my invention and how those as well as the objects hereinabove particularly pointed out are achieved will be best understood from the following detailed explanation of a presently preferred embodiment of the invention, wherein I shall refer to the accompanying drawing in which:

Fig. 1 is a side elevation partly in section;

Fig. 2 is a view slightly in perspective showing the parts disassembled;

Fig. 3 is a plan view of the guard plate;

Fig. 4 is a sectional view of the device assembled, shown partly in elevation;

Fig. 5 is a section on line 5—5 in Fig. 1;

Fig. 6 is a fragmentary enlarged section;

Fig. 7 is a plan view showing a variational form of head construction; and

Fig. 8 is a fragmentary sectional view showing a further variational form of device.

Referring now to the drawing, the three major elements of my razor are shown as comprising a guard plate 5, a blade-clamping plate 6 and a handle element 7, a conventional safety razor blade B being adapted to be clamped between the clamping plate and guard.

The guard 5 has a recess 10 disposed entirely across each end to receive the resilient undercut flanges 11 presented by the respective ends of the clamping plate 6. Said recesses 10 have the advantage of enabling the bottom edges of the

flanges to be flush with the under surface 12 of the guard plate. Preferably the guard and the clamping plate are made of a resiliently flexible material and I have found plastics to be well suited for the purpose. Many suitable plastics are well known in the art. For instance, I have found the cellulose acetate and cellulose acetate butyrate molding compounds known as "Tenite" to be suitable.

10 The top end wall 15 of the box-like handle element 7 presents an upstanding lug 16 of T-shaped section (see Fig. 5) and the handle element is comprised of hollow, telescopic sections 7a, 7b, so that it may be longitudinally adjusted to suit the desires of particular users. Moreover, such a handle provides a convenient storage space for extra blades, as well as the two head pieces when not in use. The handle sections are preferably of rectangular cross-section to provide a more effective hand-grip surface and the top end wall 15 presents at each end edge a transverse rib 17 adapted to resiliently bear against the under surface of the guard plate.

25 The clamping plate 6 is provided with a pair of depending elongated lugs 20 adapted to fit into the conventional longitudinal slot S provided in available safety razor blades.

In the guard plate I provide a central longitudinal slot 22 whose end portions are of a width to snugly receive the respective lugs 20 of the clamping plate and the medial portion of the slot 22 is T-shaped, having a stem portion 22a of a width to snugly receive the medial portion of the handle lug 16 and has a relatively wider top portion 22c of a width to receive the cross portion 16a of the lug. The under surface of the cross portion 16a of the lug and the top surface of the walls of the slot defining the stem portion of the T-slot are similarly inclined (see Fig. 6).

30 To assemble my razor, the lug 16 is inserted longitudinally in the portion 22c of the slot in the guard plate and then is slid to the right so that the T-shaped lug engages in the narrower

45 portion of the T-slot. Preferably the distance between the under surface of the cross portion 16a of the lug and the plane of the top surface of the rib 17 on the handle end wall is such as to cause the central portion of the handle end wall at and adjacent the lug 16 to flex slightly outwardly when the ribs 17 engage the under surface of the guard plate and the cross portion of the lug 16 engages in the T-slot. This causes the guard plate to be somewhat resiliently 55 clamped between the ribs 17 and the cross por-

tion of the lug and thus provides a firm mounting and also compensates for any slight wear that might take place. When the handle, guard and clamping plate are so assembled, the lugs 20 on the clamping plate project into slot 22 astride the handle lug 16, thus positively preventing sliding of lug 16 along the slot when the razor is assembled. To remove the clamping plate from the guard, the handle is held in the fingers while the thumb presses on the under surface of an end of the clamping plate to flex its flange 11 over the end of the guard plate and then the lug 16 is moved in the slot 22 until it may be longitudinally withdrawn. The handle sections engage each other with a relatively tight frictional sliding fit so that the length of the handle may be adjusted to suit the preferences of any given user. The lower end of handle 7b is provided with end flanges 7c which act as a stop against further telescoping of the handle sections and also those flanges provide means for finger engagement to pull the handle section 7b out of section 7a.

In Fig. 8 I show a different form of device wherein the under surface 41 of the T-shaped body lug 40—corresponding to lug 16 of the other views—has a double taper to provide a V-shaped slot-engaging surface. Thus the lug 40 may be engaged against the tapered wall surface 42 defining the bottom of the T-slot in the guard plate 5a regardless of which edge of the lug 40 is inserted in the slot first.

While, in the foregoing, I have resorted to considerable detail of structure and association of parts in describing a particular example of my invention, I wish it to be understood that I have done so merely to make my invention understood and that I do not limit my invention to such details. On the contrary, my invention is subject to modifications and is only to be limited as appears in the appended claims.

I claim:

1. A safety razor comprising a guard plate presenting a longitudinal slot having a T-shaped medial portion, a handle having a T-shaped end portion slidably engaging in said T-shaped medial portion of the slot, a clamping plate for retaining the razor blade against the guard plate, said last-named plate having a depending lug fitting into the longitudinal slot, and means for detachably securing the clamping plate to the guard plate.

2. A safety razor comprising a guard plate and a handle, the handle presenting a T-shaped end lug, a longitudinal slot in the guard plate, the slot having a T-shaped medial portion whereby to slidably receive the lug and an intersecting wider portion into which the lug may be inserted longitudinally preparatory to being received by the T-shaped portion, and means for clamping a blade against the outer surface of the guard plate.

3. A safety razor comprising a guard plate having a blade-receiving outer surface, the bottom surface of each end portion of the guard plate presenting an outwardly opening recess, a blade-clamping member mounted over the top surface of the guard plate, and a resilient depending flange on each end of the clamping member, each of said flanges having an inwardly disposed portion engageable in one of the respective recesses.

4. In a safety razor, the combination of a guard plate having a top blade-receiving surface, a clamping plate superimposed on the guard plate, and resilient depending means on the corners of the clamping plate having locking en-

gagement with the guard plate, the medial end portions of the plate being recessed to expose a portion of each end of the blade whereby to enable a user simultaneously to manually grip the blade and recessed ends.

5. A safety razor comprising a guard plate presenting a longitudinal slot whose medial portion is T-shaped, a handle presenting a T-shaped lug slidably engaging said slot, and a blade-clamping plate superimposed on the guard plate, said clamping plate presenting spaced depending lugs extending through the blade and into the slot astride the T-shaped lug whereby to lock the last-named lug against sliding relative to the slot.

6. A safety razor comprising a guard plate presenting a T-slot having a stem portion and a relatively wider top portion, the walls of the slot defining the stem portion having an inclined top surface, a handle having a resilient end wall presenting a T-shaped lug engageable in the slot and a pair of projections one at each side of and spaced from the lug and being engageable against the under surface of the guard plate, and means for holding a blade in position against the outer surface of the guard plate.

7. A safety razor comprising a guard plate and a handle having a resilient top end wall, a T-shaped lug carried medially on the end wall, a pair of ribs on the end wall spaced from the lugs at opposite sides thereof, the under surface of the cross portion of the lug being inclined, said plate presenting a lug-receiving T-slot having a stem portion and a relatively wider top portion, the walls of the slot defining the stem portion having an inclined surface engageable by the inclined surface of the lug, a lug-passing opening through the plate intersecting the T slot, the distance between the under surface of the cross portion of the lug and the plane of the top surface of the ribs being short enough to cause the end wall of the handle to be resiliently held in outwardly flexed position when the lug engages in the T-slot, and means for clamping a blade against the outer surface of the guard plate.

8. A safety razor comprising a blade-retaining head and a handle secured to the head, said handle being comprised of telescopic box-like portions.

9. A safety razor comprising a blade-retaining guard plate having a T-slot, a box-like handle having a resilient wall, means spacing the end portions of the wall from the under surface of the guard plate and a central T-shaped lug on said wall engaging in the slot and retaining the central portion of the wall against the under-surface of the guard plate.

10. A safety razor comprising a guard plate and a handle having a resilient top end wall, a T-shaped lug carried medially on the end wall, a pair of ribs on the end wall spaced from the lugs at opposite sides thereof, the under surface of the cross portion of the lug being inclined from its end edges towards the center whereby to present substantially a V-shape, said plate presenting a lug-receiving T-slot having a stem portion and a relatively wider top portion, the walls of the slot defining the stem portion having an inclined surface engageable by the inclined surface of the lug, a lug-passing opening through the plate intersecting the T-slot, the distance between the under surface of the cross portion of the lug and the plane of the top surface of the ribs being short enough to cause the end wall of the handle

to be resiliently held in outwardly flexed position when the lug engages in the T-slot, and means for clamping a blade against the outer surface of the guard plate.

11. A safety razor comprising a blade-retaining guard plate presenting a T-slot having a stem portion and a relatively wider top portion, the slot walls defining the stem portion having an

inclined top surface, a handle presenting a T-shaped lug slidably engageable in the slot, the under face of the cross portion of said lug being inclined from its center towards its sides whereby 5 to be engageable against the inclined top surface of the slot wall when inserted in the slot from either side of the lug.

JAN DE SWART.
